(57) **CLAIM**

The ornamental design for an fuel rail, as shown and described.

DESCRIPTION

FIG. 1 is a front view of an fuel rail section showing our new design;

FIG. 2 is a rear view thereof;

FIG. 3 is a right side view thereof;

FIG. 4 is a left side view thereof;

FIG. 5 is a top side view thereof;

FIG. 6 is a front view thereof with section lines;

FIG. 7 is a cross-sectional view along line 7-7 of FIG. 6; and,

FIG. 8 is a cross-sectional view along line 8-8 of FIG. 6.

In the drawings, the broken lines depict unclaimed subject matter only and form no part of the claimed design.
